UNITED STATES PATENT OFFICE.

GEORGE R. FOLDS, OF EVANSTON, AND JOHN S. BAKER, OF CHICAGO, ILLINOIS, AS
SIGNORS TO COOK ELECTRIC COMPANY, OF CHICAGO, ILLINOIS, A CORPORATION OF
ILLINOIS.

PROTECTIVE DEVICE.

Application filed March 16, 1923. Serial No. 625,474.

This invention relates to protective devices and more particularly to protective devices designed for use with radio apparatus.

An object of this invention is to provide a convenient assembly comprising a fuse, lightning discharger, and grounding switch all mounted as a unit upon a single block of insulation.

In devices of this character now in use, the more usual practice is to attempt to utilize a single element for protection against both excessive voltages and excessive currents. An object of this invention, however, is to provide a lightning discharger for discharging high voltages from the antenna to the ground and to provide in addition a fuse of low current carrying capacity to especially protect the radio receiving apparatus against excessive currents of a potential too low to operate the lightning discharger.

A further object of this invention is to provide suitable connections in the above indicated type of protective device in order that the lightning discharger will be at all times interposed between the antenna and ground terminals.

Another object of this invention is to provide suitable connections in an assembly of the type above indicated in order that the radio receiving apparatus may be completely disconnected from the antenna when not being used.

A still further object of this invention consists in the production of an improved, efficient and durable device of the character indicated, which may be readily assembled and which is low in manufacturing cost.

This invention is directed to the accomplishment of the aforementioned objects and others hereinafter appearing and for a better understanding of the same, reference may be had to the following description and to the accompanying drawing, in which—

Figure 1 is a plan view of an assembled unit embodying the invention;

Fig. 2 is a bottom view of the device, shown in Fig. 1;

Figs. 3 and 4 are sectional views taken respectively upon the lines 3—3 of Fig. 1 and 4—4 of Fig. 3;

The various parts of the device may be mounted upon an insulation base 10 composed preferably of porcelain or other refractory material.

As shown, the base 10 may be provided with connection terminals 11, 12 and 13 for attachment respectively of the antenna ground wire and receiving apparatus leads. These terminals may preferably be located substantially at the corners of the base 10 within depressions 14, 15 and 16, respectively, formed in the porcelain which serve to conveniently receive these terminals and retain them in position and proper alignment.

Between the antenna terminal 11 and the ground terminal 12 a gap lightning arrester 17 may be electrically connected. The leads to the arrester 17 may be permanently fixed to the terminals 11 and 12, or as shown, may be formed integral therewith and thereby insure the positive maintenance at all times of a path for permitting high voltages to be discharged from the antenna to the ground terminal. The lightning arrester 17 may be of the type shown in the patent to G. R. Folds, 1,438,954, December 19, 1922.

Since the detail construction of this arrester itself forms no part of this invention, it will not be here described in full. In general, this arrester comprises conductor strips 18 and 19 between which a block of carbon 20 and a conducting strip 21 are retained. The carbon block 20 is insulated and slightly spaced from the conducting strip 21 by a thin layer of insulation such as celluloid, or other dielectric at 22. The conducting strip 21 may be fitted with a discharge electrode at 23, which is maintained in a slightly but accurately spaced relation with a portion of the carbon block 20, the conducting strip 21 being formed with flanges at 24 for securely clamping this strip in place upon the carbon block. The discharge electrode at 23 and the carbon block 20 thus serve together to form a short spark gap by means of which high voltages, such as would damage a radio receiving set, are readily discharged from the antenna to the ground terminal.

The lightning arrester 17 may be positioned within a metallic cap 25 lined with sheet fibre insulation 26. The cap 25 may be frictionally retained within a recess 27 formed within the base 10. The base 10 may also be formed with channel ways 28 and 29 for receiving and retaining in position the connecting strips 18 and 19, respectively. It will thus be seen that a durable and rigid assembly is provided between the terminals 11

and 12, the lightning arrester 17 and the various mechanical and electrical connecting and housing parts.

A further connection terminal 30 similar to the terminal 11 may be provided at the remaining corner of the base 10. Between the terminals 11 and 30, a fuse 31 and fuse clips 32 and 33 may be mounted. The detail construction of the particular fuse and fuse clips which may be used at this point forms no part of the present invention, but may be of the general character shown in the patent to F. B. Cook, 843,930, Feb. 12, 1907, comprising a small fusible wire within a protective housing. The fuse should be designed with a carrying capacity sufficiently low to cause the fuse to be burned out by any considerable current such as might destroy the receiving apparatus.

20 A single pole, double throw switch of any suitable and approved type may be interposed between the ground terminal 12 and the receiving apparatus terminal 13, a hinged post 34 for this switch being positioned midway between terminals 12 and 13 and the terminals 12 and 13 being formed with knife switch blades 35 and 36, respectively, for receiving a switch blade 37. A connection 38 on the back of the base 10 may serve to electrically connect the terminal 30 to the hinged post 34.

It will be noted that the switch as shown may be used to connect the fuse 31 in series with the antenna and the receiving apparatus through the terminal 13 or when the receiving apparatus is not being used, the switch may be thrown to terminal 12 whereby the receiving apparatus is entirely disconnected from the antenna and ground terminals and the antenna is thereby grounded through the connection 38 and the fuse 31.

The ways in which this device as shown and described, serves to protect a receiving or other radio apparatus which may be attached to the terminal 13 will now be more fully described. When the receiving apparatus is not in use, it will be entirely disconnected from the antenna and ground and therefore it will be impossible for any unusual currents from these sources to injure the apparatus. At the same time, the antenna will be directly grounded through the fuse and switch, thereby avoiding the possibility of the accumulation of any excessive charges upon the antenna. The gap arrester 17 also will be interposed between the antenna and ground for lightning protection while the receiving apparatus is not in use.

When the switch is thrown to the operative position, the receiving apparatus is thereby placed in series with the fuse and antenna. The gap arrester 17 continues to offer the same protection as when the switch is in the inoperative position. The fuse, however, offers the additional protection from

excessive currents of a voltage insufficient to pass over the gap arrester 17.

In addition to the electrical advantages of the assembly of the type described, it is also obvious that a very logical, durable and compact mechanical assembly of the parts results, whereby the switch may be positioned in an easily operable location along one edge of the base and the fuse may be placed in a symmetrical position at the edge opposite from the switch on the base. The lightning arrester furthermore may be placed between the switch and fuse and is thereby provided with a mechanically protected position wherein it may be very readily electrically and mechanically associated with the ground and antenna terminals.

While we have shown and described but one embodiment of our invention, it is to be understood that we do not desire to be limited to the specific method and apparatus mentioned, but that we desire only such limitations to be imposed upon our invention as are set forth in the appended claims.

Having thus described our invention, what we claim as new and desire to secure by Letters Patent in the United States, is:

1. In a radio circuit, an antenna terminal, a ground terminal, a receiving apparatus terminal, means for constantly maintaining a path for high voltage currents between said antenna and said ground terminals, means connected to said antenna terminal for protection of the receiving apparatus from excessive currents, and a switch for connecting said last named means in series with the receiving apparatus terminal or for disconnecting the receiving apparatus terminal and connecting said last named means to said ground terminal.

2. In an article of manufacture comprising a protective device for radio apparatus mounted on a base having antenna and ground connections, means for constantly maintaining a path for high voltage currents between the antenna and ground connections, means connected to the antenna connection for protection against excessive currents, and a switch for connecting said last named means in series with the radio apparatus or for disconnecting the radio apparatus and grounding said last named means.

3. A protective unit for radio installations comprising an antenna terminal, a ground terminal, a receiving apparatus terminal, a high voltage arrester bridging said antenna and ground terminals, means for protection against excessive current, one end of said means being connected to said antenna terminal, and a switch for alternatively connecting the other end of said means to said ground terminal or to said receiving apparatus terminal.

4. A protective unit for radio installations comprising an antenna terminal, a ground

terminal, an apparatus terminal, a gap arrester bridging said antenna and ground terminals, a fuse one end of which is connected to said antenna terminal, and a switch for 5 alternatively connecting the other end of said fuse to said ground terminal or to said apparatus terminal.

5. An article of manufacture comprising an elongated insulated base, a single pole double throw switch mounted along one edge of the face of said base, a fuse member mounted along the opposite edge of the face of said base, and a gap lightning arrester mounted between said switch and said fuse member, 10 said switch, fuse member and lightning arrester being electrically interconnected for association with a radio antenna circuit.

6. An article of manufacture comprising an insulation base; fuse, antenna, ground, 20 and apparatus terminals respectively positioned substantially at successive corners of said base; a fuse, an arrester, and a single pole double throw switch positioned respectively between successive pairs of said terminals for 25 alternately positioning said fuse either between said ground terminal and antenna terminal or between said apparatus terminal and said antenna terminal.

7. An article of manufacture comprising an insulation base; fuse, antenna, ground and apparatus terminals respectively positioned substantially at successive corners of said base; a fuse, an arrester, and a single pole double throw switch positioned respectively 35 between successive pairs of said terminals, said base being formed with depressions for receiving and retaining in position said terminals and said arrester.

8. A protective unit for radio installations 40 comprising an insulation base member, an

antenna terminal, a ground terminal, a receiving apparatus terminal, said terminals being positioned substantially at corners of said base member, a gap arrester positioned between and bridging said antenna and ground terminals, said base being provided with depressions for receiving and retaining in position said terminals and said gap arrester, means for protection against excessive current comprising a fuse connected at one 50 end of said antenna terminal, and a single pole double throw switch for alternatively electrically connecting the other end of said means to said ground terminal or to said receiving apparatus terminal. 55

9. A protective unit for radio installations comprising an insulation base member, an antenna terminal, a ground terminal, a receiving apparatus terminal, said terminals being positioned substantially at corners of 60 said base member, a gap arrester positioned between and bridging said antenna and ground terminals, said base being provided with depressions for receiving and retaining in position said terminals and said gap arrester, means for protection against excessive current comprising a fuse connected at one end to said antenna terminal, and a single pole double throw switch for alternatively 65 electrically connecting the other end of said means to said ground terminal or to said receiving apparatus terminal, said switch being positioned and extending between said ground and apparatus terminals, said fuse being positioned parallel to said switch at the 70 opposite edge of said base member. 75

In witness whereof, we have hereunto subscribed our names.

GEORGE R. FOLDS.
J. S. BAKER.
